DESIGN FOR A TIRE

Charles P. Wilcox, Mansfield, Ohio, assignor to
The Fisk Rubber Corporation, Chicopee Falls,
Mass., a corporation of Delaware

Application January 10, 1936, Serial No. 60,520

Term of patent 14 years

To all whom it may concern:

Be it known that I, Charles P. Wilcox, a citizen of the United States, residing at Mansfield, in the county of Richland and State of Ohio, have invented a new, original, and ornamental Design for a Tire, of which the following is a specification, reference being had to the accompanying drawing, forming part thereof.

Fig. 1 is a perspective view of a tire showing

my new design, a complementary portion being illustrated in dotted lines;

Fig. 2 is a plan developed view of a portion of a tire showing my design; and

Fig. 3 is a transverse radial section of a tire taken substantially on line 3—3 of Fig. 2.

I claim:

The ornamental design for a tire as shown.

CHARLES P. WILCOX.
